Primary Examiner — Kimberly Barnes

(74) Attorney, Agent, or Firm — Daniel M. Cohn;
Howard M. Cohn

(57) **CLAIM**

The ornamental design for a portable mini car vacuum cleaner as shown and described.

DESCRIPTION

FIG. 1 is a perspective view of a portable mini car vacuum cleaner showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof; and,

FIG. 9 is a perspective view thereof shown in an environment of use.

The broken lines in FIGS. 1-6 depict portions of the portable mini car vacuum cleaner that form no part of the claimed design. The broken lines in FIG. 9 depict environmental subject matter that forms no part thereof.

1 Claim, 9 Drawing Sheets
